**APPARATUS FOR MOVING WORK THROUGH A
CONTINUOUS REHEATING FURNACE**

Julius B. Evans, Chicago, Ill., assignor to United States Steel Corporation, a corporation of Delaware
Filed Dec. 20, 1966, Ser. No. 603,376
8 Claims. (Cl. 263—8)

ABSTRACT OF THE DISCLOSURE

A conveyor arrangement for carrying semifinished steel shapes through a reheating furnace. Conveyors formed of ceramic blocks mounted in metal casings coupled to form two endless strands, which travel through the furnace in water-cooled troughs. Strands parallel through most of the furnace length, but diverge near discharge end to deposit work on a hearth, from which it slides down an incline and leaves the furnace. Main purpose is to eliminate "skid-marks" from the work. These marks are cool spots which result when the work travels through furnace on conventional water-cooled skids.

This invention relates to an improved apparatus for moving semifinished metal shapes through a continuous reheating furnace.

A conventional continuous reheating furnace includes an enclosed elongated chamber through which work travels from the charging end to the discharge end. The work is supported on water-cooled skids which extend the major portion of the length of the furnace. The furnace chamber is divided into several combustion zones situated both above and below the skids. One of the problems in operating this type of furnace is that areas on the bottom of the work contacted by the skids tend to remain cooler than the rest of the work. These cool spots, known as "skid marks," interfere with subsequent rolling operations.

An object of the present invention is to provide an improved apparatus for moving work through a continuous reheating furnace, which apparatus substantially eliminates skid marks from the work.

A further object is to provide an apparatus for moving work through a furnace in which I replace the usual skids with a pair of endless ceramic block conveyor strands.

A more specific object is to provide an apparatus of the foregoing type in which the strands travel through water-cooled troughs as they pass through the furnace and automatically deposit the work on a hearth near the discharge end of the furnace.

In the drawings:

FIGURE 1 is a side elevational view with parts broken away of a continuous reheating furnace equipped with my apparatus for moving the work therethrough;

FIGURE 2 is a horizontal section on line II—II of

FIGURE 1;

FIGURE 3 is a partial vertical cross section on a larger scale on line III—III of FIGURE 1 with the furnace parts omitted for clarity;

FIGURE 4 is a side elevational view with parts broken away of two of the links which make up my conveyor strands; and

FIGURE 5 is a bottom plan view of a link.

FIGURES 1 and 2 show a continuous reheating furnace which includes side walls 10, a roof 12, and a bottom wall 13.

The chamber of the furnace illustrated has two upper heating zones 14 and 15 and one lower heating zone 16, which are equipped with conventional burners 19, although the number of zones may vary. Products of combustion from the burners leave the furnace chamber through a

2

flue 20 near the charging end (the right as viewed in FIGURE 1). Preferably the furnace is of a type in which the flue extends upwardly from the roof to avoid obstructions beneath the furnace. Work W (for example, steel slabs or billets) enters the furnace through a door 21 at the charging end, travels the length of the furnace and across a short-length hearth 22, slides down a sloping apron 23, and discharges through a door 24. A conveyor 25 carries the heated work from the furnace. Apart from my apparatus for moving the work, the furnace can be of conventional construction, and hence is not shown in detail.

My apparatus for moving work through the furnace comprises a pair of endless conveyor strands 26 and 26a, the carrying flights of which travel through the furnace in water-cooled troughs 27 and 27a respectively. I support the troughs on a plurality of water-cooled pipes 28 which extend upwardly from the bottom wall 13 and are of inverted U-shape. The troughs extend into the furnace immediately below the charging door 21. They are parallel through most of the length of the furnace, but diverge opposite the hearth 22, as indicated at 30. They extend out the furnace through openings 31 in the side walls 10 near the discharge end. The trough portions outside the openings 31 again become parallel, as indicated at 32. The extremities of the troughs slope upwardly, as indicated at 33, and are connected to water inlet and outlet pipes 34 and 35 outside the charging and discharge ends of the furnace respectively. After leaving the troughs, the strands 26 and 26a travel around power-driven sprockets 36 and idler rollers 37 journaled on horizontal axes. The sprockets 36 propel the strands, and together with the rollers, direct their return flights beneath the furnace. In their return flights the strands converge around inside and outside guide rollers 38 and 39 journaled beneath the furnace on vertical axes. Subsequently the strands travel around other idler rollers 40 and 41 which are journaled on horizontal axes and direct the strands into the troughs 27 and 27a at the charging end. Preferably the strands ride along supports 42 to prevent their sagging as they travel between rollers 39 and 40.

FIGURES 3, 4 and 5 show the construction of strand 26 and trough 27 in more detail. The other strand and trough are similar, except of opposite hand. I form strand 26 of a large number of links, each of which includes a cylindrical ceramic block 43 and a metal casing 44 for the block. The ceramic material can be any which can sustain the weight of the work at the furnace temperature, such as silicon carbide. The exterior of each casing carries an eye 45 and a diametrically opposed hook 46. Each hook engages the eye of the adjacent casing to join the links together, but permit relative movement both horizontally and vertically. Trough 27 is formed of metal and is T-shaped in cross section. The bottom wall of the trough carries a series of opposed pairs of bearing lugs 47 in which are journaled rollers 48. The inside faces of the side walls carry bearing strips 49. The bottom faces of blocks 43 ride on rollers 48, and the side faces of the casings 44 ride against strips 49. The bottom face of each block has notches 50 spaced to receive the teeth of sprocket 36.

Along its upper edges trough 27 has opposed inwardly facing channels 52 which project outwardly from the body of the trough. Each casing 44 carries a cover plate 53, the side edges of which fit within these channels. The leading portion of each cover plate is offset upwardly from the trailing portion and overlaps the trailing portion of the adjacent cover plate. The upper flanges of channels 27 terminate at the beginning of the sloping sections 33 in order not to interfere with the cover plates 53 as the links of strand 26 enter and leave trough 27. The leading edge of each cover plate has a concave recess 54 (FIGURE 5) which receives the adjacent block 43. The trail-

ing edge is rounded, as indicated at 55. Thus the cover plates effectively enclose the top of trough 27 and confine water therein without interfering with relative movement of the blocks.

The furnace has short-length skids 56 which extend from door 21 at the charging end above a portion of the plane of strands 26 and 26a (FIGURES 1 and 2). These skids slope downwardly at a gradual angle from the door to the strands. The work W enters the furnace on these skids, along which it can be pushed with conventional equipment, not shown. The skids deposit the work gently on the strands, which are driven continuously at a speed properly coordinated with the rate at which the work is introduced. Thus the work does not drop on the ceramic blocks 43 in a way likely to cause damage. The strands reach approximately the same temperature as the work and do not cool the work in areas of contact and cause skid marks. Troughs 27 and 27a, their supports 28 and the metal parts of the strands are water-cooled and remain at a sufficiently low temperature that the furnace heat does not damage them. The strands carry the work to the hearth 22, where they diverge at 30 beyond the ends of the work and deposit the work on the hearth. Oncoming work abuts that which has been deposited and thus pushes this work to the apron 23. Finally the work slides down the apron and out door 24, where it is received on suitable handling equipment, such as the conveyor 25 illustrated.

While I have shown and described only a single embodiment of my invention, it is apparent that modifications may arise. Therefore, I do not wish to be limited to the disclosure set forth but only by the scope of the appended claims.

I claim:

1. In a continuous reheating furnace which includes: 35 walls defining a chamber having charging and discharge ends; and a hearth within said chamber near said discharge end; the combination therewith of an apparatus for moving work through said chamber, said apparatus comprising: 40 a pair of endless conveyor strands formed of links connected together to permit relative movement both horizontally and vertically; each of said links including: 45 a cylindrical ceramic block on which the work rests; a metal casing for said block; and an eye and a diametrically opposed hook carried by said casing; the hook of each link engaging the eye of the adjacent link; 50 said strands having carrying flights within said chamber and return flights beneath said chamber;

water-cooled means within said chamber supporting and guiding said carrying flights; and means outside said chamber engaging said strands for propelling them and guiding said return flights; said carrying flights extending in parallel relation from said charging end to said hearth and diverging opposite said hearth to carry work from said charging end and deposit it on said hearth.

2. A combination as defined in claim 1 in which said water-cooled means includes metal troughs extending through said walls at said charging end and near said discharge end, a plurality of pipes of inverted U-shape within said chamber on which said troughs are mounted, and water inlets and outlets connected to said troughs outside said walls.

3. A combination as defined in claim 2 in which said troughs have opposed inwardly facing channels along their upper edges and said links include respective overlapping cover plates, the side edges of which plates are received in said channels to confine water in said troughs.

4. A combination as defined in claim 2 including a plurality of rollers journaled in said troughs, said links riding on said rollers.

5. A combination as defined in claim 1 in which the means for propelling said strands includes respective power driven sprockets outside said discharge end over which said strands pass, said links having sprocket-engaging notches in their bottom faces.

6. A combination as defined in claim 1 in which the means for guiding the return flights includes idler rollers journaled on horizontal axes outside each end of said chamber, and inside and outside guide rollers journaled on vertical axes beneath said chamber, said strands passing around said rollers.

7. The combination as defined in claim 1 in which said chamber has a flue extending upwardly to avoid obstructions beneath.

8. A combination as defined in claim 1 including downwardly sloping skids extending from the charging end over said strands to place the work gently on the strands as it enters said chamber.
